UNITED STATES PATENT OFFICE.

RICHARD BIRKHOLZ, OF MILWAUKEE, WISCONSIN, ASSIGNOR TO LIQUID CARBONIC ACID MFG. CO., OF CHICAGO, ILLINOIS.

APPARATUS FOR CLEANSING FAUCETS AND THEIR CONNECTIONS.

SPECIFICATION forming part of Letters Patent No. 680,836, dated August 20, 1901.

Application filed June 1, 1900. Serial No. 18,719. (No model.)

To all whom it may concern:

Be it known that I, RICHARD BIRKHOLZ, a citizen of the United States, residing at Milwaukee, in the county of Milwaukee and State 5 of Wisconsin, have invented certain new and useful Improvements in Apparatus for Cleansing Faucets and Their Connections, of which the following is a specification, reference being had to the accompanying drawing, forming 10 ing a part thereof.

My invention relates particularly to apparatus for cutting or loosening and removing the viscous deposits and other impurities which collect in beer-dispensing faucets and 15 their pipe or hose connections leading from the kegs or barrels from which the beer is drawn. Its main objects are to facilitate changing the connections for cleansing the dispensing apparatus and for drawing beer or 20 other liquid to be dispensed, to save time, and to avoid waste both of the beer or liquid to be dispensed and of the cleansing materials.

It consists in certain novel features in the construction and arrangement of component 25 parts of the apparatus, as hereinafter particularly described, and pointed out in the claims.

The accompanying drawing shows a vertical section of my improved cleansing apparatus as applied to a beer-dispensing faucet 30 and its connections commonly used in bar-rooms and saloons.

A designates a dispensing-faucet attached in the usual manner to a bar-fixture; B, a hose attached by a coupling at one end to the inner end of said faucet and at the other end by a like or similar coupling to one end of a pipe C, which is adapted to be inserted in a beer barrel or cask D through the bung-hole in one head thereof. The pipe C is provided at its 35 upper end next to the hose B with a stop-cock c, and at its opposite end is formed with a number of small holes to allow the beer or other liquid to flow into it at or near the bottom of the barrel or keg in which it is inserted.

E is a tapered plug which is adapted to be driven into and tightly close the bung-hole in the head of the keg or barrel and through 40 which the pipe C passes, said plug being provided in the usual manner with suitable means for forming a fluid-tight joint between

it and the pipe C and having on one side a hose connection e, to which one end of a hose F is attached. The passage in the hose connection e leads through the inner end of the 55 plug E around or outside of the pipe C into the barrel or keg in which said plug is inserted. The other end of the hose F is attached to the spout of a cock G, which is connected with an air or gas supply pipe H. 60

The apparatus above described being such as is commonly used in bar-rooms and saloons for dispensing beer does not in itself constitute my invention.

In connection with the above-described apparatus I provide a stationary liquid-receptacle I, which may be conveniently made of a piece of metal pipe three inches, more or less, in diameter, fitted and secured at the ends by any suitable means in castings which form 70 the base and top of the receptacle. This receptacle is preferably made of a length corresponding approximately with the length of the barrels or casks D, with which the dispensing apparatus is intended to be employed. At or near its bottom the receptacle 75 I is provided with a waste-cock J, and at or near its top a water-service pipe K, provided with a cock k, is permanently attached thereto. In the upper end of the receptacle I is 80 inserted a wooden plug or bushing L, having a conical hole through it corresponding with the bung-holes in the heads of the barrels or kegs D, into which the tapered plug E is adapted to be tightly driven. This wooden 85 plug or bushing L may be held in place by a flanged metal cap or ring l, fitted over and secured to the casting forming the upper end of the receptacle I.

M is a sheet-metal pail or receptacle provided with a bail and a spout m for pouring the soda solution or other cleansing liquid into the receptacle I and catching the same as it is discharged from the faucet A.

My improved apparatus operates as follows: 90 When it is desired to cleanse the faucet A, hose B, pipe C, and their connections, the receptacle I is filled or supplied with a soda or other cleansing solution from the pail or bucket M, the spout m of which is inserted 100 in the hole of the wooden plug or bushing L. The pipe C and plug E having been removed

from the barrel from which the beer or other liquid has been drawn are inserted in the receptacle I, as shown at the left in the drawing, and the plug E is driven tightly into the wooden plug or bushing L and the packing therein tightened upon said pipe. The cock G, which has been previously closed, is now opened, and air or other gas under pressure is admitted from the pipe H through the hose F into the top of receptacle I. The cock c being opened, the solution is forced from the receptacle I into the pipe C and hose B, the faucet A being opened slightly to allow air and foam to escape from said pipe and hose. The solution is held in the pipe C and hose B a short time—long enough to allow it to cut and loosen the viscid matter and other impurities contained therein. The faucet A is then opened and the solution, with the loosened impurities, is drawn off into the pail or bucket M. The faucet A is closed when the air or other gas employed begins to issue therefrom. The gas-cock G is now closed and the water-cock k is opened, allowing water under a greater pressure than that to which the air or gas is subjected in pipe H to flow from pipe K into the receptacle I. The pail M, in which the solution has been caught and saved, having been removed, the faucet A is again opened and water allowed to flow until said faucet and its connections are thoroughly cleansed and rinsed. The faucet A and the cock k are now closed and the waste-cock J is opened, allowing the water to drain from the hose B, pipe C, and receptacle I. When this has been done, the pipe C and plug E are withdrawn from the receptacle I and inserted in another barrel D, as shown at the right in the drawing, the cock c having been previously closed. The plug E having been driven into the bung of the barrel and the packing therein tightened upon the pipe C, the cocks c and G are opened and the apparatus is in condition for drawing beer or other liquid from the barrel in the usual way.

The impurities drawn off with the cleansing solution into the pail M may be allowed to settle therein and the clear solution decanted from above them when the receptacle I is again filled, the sediment remaining in the pail being washed out. In this way the same solution will serve over and over again to cut and loosen the viscid matter collecting in the dispensing apparatus.

It will be evident that a single cleansing apparatus may be employed with a number of dispensing-faucets and their connections and that any one of the faucets and its connections may be cleansed in the manner above explained without interfering with the operation of the other faucets and their connections. It will also be observed that in transferring the pipe C and plug E from a barrel D to the receptacle I, or vice versa, it is unnecessary to detach or disturb the connections of the hose B and F.

Various modifications in the minor details

of construction and arrangement of parts of the apparatus may be made without materially affecting its operation and without departing from the spirit and intended scope of my invention.

I claim—

1. The combination with liquid-dispensing apparatus comprising a pipe or tube having a flexible connection with a faucet, and a sealing device having a flexible connection with a compressed-gas supply for securing said pipe by a fluid-tight joint in a barrel, of a receptacle for a cleansing liquid to which said pipe and its sealing device are adapted to be transferred from the barrel without disturbing their connections with said faucet and with the gas-supply, said receptacle having a permanent valve-controlled water-supply connection, substantially as and for the purposes set forth.

2. The combination with liquid-dispensing apparatus comprising a pipe having a flexible connection with a faucet and a hollow tapered plug having a flexible connection with a compressed-gas supply for sealing said pipe in the bung-hole of a barrel and supplying gas under pressure thereto, of a receptacle for a cleansing liquid having a permanent valve-controlled water-supply connection and an opening in the top in which said pipe and plug are adapted to be secured without disturbing their connections with said faucet and gas-supply, substantially as and for the purposes set forth.

3. The combination with liquid-dispensing apparatus comprising a pipe having a flexible connection with a faucet, and a tapered plug having a flexible connection with a compressed-gas supply and adapted to secure and seal said pipe in the bung-hole of a barrel, of a fixed receptacle for a cleansing liquid having a permanent valve-controlled water-supply connection, an opening in the top to receive said pipe and plug, and a valve-controlled waste opening or connection at or near the bottom, substantially as and for the purposes set forth.

4. The combination with liquid-dispensing apparatus comprising a faucet, a tapping-pipe having a valve-controlled hose connection with said faucet, a compressed-gas supply, and a tapered plug having a valve-controlled hose connection with said gas-supply and adapted to secure and seal said pipe in the bung-hole of a barrel, of a metallic receptacle having a valve-controlled water-supply connection and a wooden top with an opening corresponding with the bung-hole of a barrel and adapted to receive said pipe and plug, substantially as and for the purposes set forth.

In witness whereof I hereto affix my signature in presence of two witnesses.

RICHARD BIRKHOLZ.
